UNITED STATES PATENT OFFICE.

CHARLES L. McVOY, OF PENSACOLA, FLORIDA.

RAIL-JOINT.

No. 897,921

Specification of Letters Patent.

Patented Sept. 8, 1908.

Application filed October 4, 1907. Serial No. 395,949.

To all whom it may concern:

Be it known that I, CHARLES L. McVoy, a citizen of the United States, residing at Pensacola, in the county of Escambia and State of Florida, have invented certain new and useful Improvements in Rail-Joints; and I do hereby declare the following to be a full, clear, and exact description of the invention, such as will enable others skilled in the art to which it appertains to make and use the same.

This invention relates to the improvements in steel rails and is primarily designed in order to provide an effective joint between the abutting ends of the rails in such manner that not only are the rail ends secured together, but also that the rails at their joints are reinforced against lateral strain.

Other objects and advantages of the invention will be observed from the following description and the novel features will be more succinctly pointed out in the claims.

Broadly speaking, the invention comprises the provision of a projection or tongue disposed longitudinally of the web and adapted to rest beneath the tread of the opposite rail.

While I do not restrict myself to the exact details shown and described, still for the purpose of disclosure, reference is had to the accompanying drawings illustrating a practical embodiment of the invention and in which—

Figure 1. is a perspective view of a portion of a pair of rails constructed in accordance with my invention and the abutting ends of which are fitted and bolted together. Fig. 2. is a disassociated view of the complementary ends of the rails to be joined, Fig. 3. is a transverse sectional view through the rail joint, and Fig. 4. is a perspective view showing more clearly the shoulder formed by the vertical web of the rail and the side tongue.

In the drawings there is illustrated the usual form of rail, comprising the tread 1, the base flange 2, and the vertical web 3. The vertical web 3, is provided near its end with an enlarged reinforcing portion extending longitudinally beyond the end of the rail as at 5, forming a tongue. It will be observed that each rail at their abutting ends may be provided with one of these reinforced portions and extending tongues on opposite sides, and the other ends of the rails may be similarly provided with the same parts reversed.

When assembled, as clearly shown, the ends of the abutting vertical webs as at 6, and

the ends of the treads and base flanges, will lie substantially in the same vertical plane, and the tongues or extensions 5, will project on opposite sides within the space formed between the tread and base flange, so that these tongues 5, will lie snugly against the sides of the vertical web and will when bolted in position coöperate with the integral enlargement on the opposite side of the web to form a rigid reinforcement at the joinder of the rails.

One of the rails and extensions may have squared apertures therein, as at 7, to receive the squared heads of bolts, and the other rail may simply have round bolt holes 8, alining with the squared ones. Through these alining bolt holes are passed the usual bolts 9, for securing the ends of the rail together. Of course, the squared bolt holes are merely a matter of detail and may be round if desired.

I am aware of the fact that there may be patents having projecting tongues at the ends of the rails, but these constructions are not the same as the present invention and they will not accomplish the same results. For instance, under the old constructions such a rail could not be associated with an ordinary rail because the projecting end would throw the tread portions out of alinement. In the present construction, however, the arrangement is such that the tread portion would remain in alinement, and in consequence the rail could be associated with a rail of the ordinary type, a fish plate being used for the projecting tongue of the old rail.

What I claim is:—

1. A rail joint composed of two abutting rail ends each consisting of a base flange, an intervening web and a tread, each of which parts are continuous and extend to the extreme rail end; said rail ends also provided on opposite sides thereof with integral side tongues, extending longitudinally beyond the rail ends proper; each of which tongues are adapted to fit snugly between the treads and base flanges of said rail ends and to be supported by said base flanges throughout their whole length; and suitable fastenings passing through said webs and tongues; whereby each rail end is supported by the base flange of the other throughout the extent of its projecting tongue, substantially as described.

2. In a rail joint the combination of a pair of rails, each comprising a base flange, a tread and an intervening web all terminating in

the same vertical plane at the respective ends of said rails, and each of said rails being provided at their ends, on opposite sides, with apertured tongues 5 extending longitudinally beyond the end of the rail and disposed parallel to but out of alinement with the web portion and forming with said web the shoulder 6, and bolts coöperating with apertures in said tongues and with apertures formed in 10 said webs to securely bolt said tongues to the webs of their opposed rail with the tongues

lying snugly against the webs and base flanges on opposite sides for their whole lengths, whereby each rail end is supported by the base flange of the other, substantially 15 as described.

In testimony whereof, I affix my signature, in presence of two witnesses.

CHARLES L. McVOY.
